UNITED STATES PATENT OFFICE.

ALBERT E. GUY, OF TRENTON, NEW JERSEY, ASSIGNOR TO DE LAVAL
STEAM TURBINE COMPANY, OF NEW YORK, N. Y.

PUMPING APPARATUS.

No. 820,779.

Specification of Letters Patent.

Patented May 15, 1906.

Application filed April 3, 1905. Serial No. 253,445.

To all whom it may concern:

Be it known that I, ALBERT E. GUY, of Trenton, Mercer county, New Jersey, have invented a new and useful Improvement in Pumping Apparatus, of which the following is a specification.

High-speed rotary fluid-impelling devices, such as centrifugal pumps, frequently fail to work properly because the velocity of the rotary impeller is so great that suction becomes imperfect. If, however, the incoming liquid be accelerated, and so brought to higher pressure, this difficulty is overcome.

My present invention consists in a moving liquid-impelling member, such as the runner of a centrifugal pump, a casing therefor having a clearance-space between said member and said casing constructed to permit a regurgitation of a part of the flow delivered by said member, and means actuated by said regurgitating flow for accelerating the fluid-supply to said impelling member, also in the embodiment of said last-named means in an injector actuated by said regurgitating flow, also in the construction of said injector and the various combinations more particularly pointed out in the claims. By reason of this construction I am enabled to drive a centrifugal pump at high speed directly from an elastic-fluid turbine, and so to deliver liquid at high pressure, which is advantageous for many special purposes—as, for example, boiler feeding and pumping against high heads.

In another application for Letters Patent, Serial No. 253,444, filed simultaneously herewith I have described and claimed, broadly, the combination of a pump and means actuated by a portion of the liquid delivered thereby for increasing the pressure of the liquid on the suction side of the pump.

In the accompanying drawings, Figure 1 is a vertical section on the line $x-x$ of Fig. 2, and Fig. 2 is a section on the line $y-y$ of Fig. 1.

Similar numbers of reference indicate like parts.

1 is the impeller wheel or runner of a centrifugal pump. The shaft 2, on which the hub 3 of said wheel is secured, is journaled in the walls of the casing 4 and is actuated by any suitable motor. Said wheel consists of an exterior ring 5, a hub 3, and impeller-blades 6 between hub and ring. As the present apparatus is duplex, the resulting com-

plete wheel has two rings 5 7, two sets of 55 blades 6 8, and a hub 3, which is of largest cross-section at its middle portion. Between the rings 5 7 is the discharge-opening 9. The internal diameter of each ring gradually decreases and then gradually increases in the 60 direction of liquid-flow and is at a maximum at the inner ends of the rings, which form the boundaries of the discharge-opening 9. The surface of the hub 3 conforms generally to the inner contour of the rings, except at the ends 65 of the hub, which are ogival. It will be seen that by reason of this construction the inlet-passages of the wheel gradually become constricted until the ends of the hub are reached, when they become annular, and that then 70 these annular passages increase in circumference, and so curve outwardly to the discharge-opening 9. Hence the liquid-flow traversing these passages becomes increased in velocity before it reaches the impeller-blades, which are arranged in the discharge-opening 9 and extend into the annular 75 passages. Said blades serve also to connect the rings and hub together.

The liquid from the suction-pipe 11 passes 80 to the branch pipe 12 and 13. At the ends of said branch pipes are contracted nozzles 14 15, which enter the flared ends of the rings 5 7. The nozzle ends are smaller in diameter than the rings, so that annular passages 16 85 are formed between nozzles and rings. These passages communicate with a chamber 17, which surrounds the wheel, and this chamber 17 communicates with the circular delivery-chamber 18, which in turn communicates 90 with the delivery-pipe 19.

It will be obvious that each nozzle, as 14, and the surrounding ring, as 5, form an injector, one wall of which—namely, the nozzle—is stationary and the other wall of which—95 namely, the ring—is rotary, or, in other words, a part of the injector is also a part of the impelling device and another part of the injector is a part of the inlet-pipe, which, as is here shown, may be integrally a part of the 100 wheel-casing.

The operation of the apparatus is as follows: The liquid drawn in by the rotation of the impelling-wheel, as indicated by the arrows, passes into the rings 5 and 7, is augmented in velocity in the annular passages, and is delivered by the blades into the chamber 18, and so to the outlet-pipe 19. A por-

tion of the liquid under pressure in the delivery-chamber passes therefrom to the chamber 17, and so through the annular passages 16 around the nozzles 14, 15. This liquid then imparts its kinetic energy to the flow entering the wheel from the nozzles 14, 15, and in this way the initial pressure of the liquid passing to the blades is increased. Inasmuch as a comparatively small augmentation of initial pressure may be sufficient for the purpose in view, the wheel may be disposed in its casing with no more clearance around it than is necessary to insure its free rotation—that is to say, the clearance 15 which would necessarily exist between the inner periphery of the rings and the nozzles and the outer periphery of rings and casing will of itself sufficiently produce the spaces heretofore designated as the "passages" 16 and "chamber" 17 to permit the requisite flow of fluid from delivery-pipe to wheel-inlet, or, in other words, the normal regurgitation of liquid due to leakage around a rotary impelling-wheel may by the above-described 20 means be utilized to increase the kinetic energy of the liquid-supply.

I claim—

1. A moving liquid-impelling member, a casing therefor having a clearance-space between said member and said casing constructed to permit a regurgitation of a part of the flow delivered by said member, and means, actuated by said regurgitating flow, for accelerating the fluid-supply to said impelling member.
2. A moving liquid-impelling member, a casing therefor having a suction-passage and a clearance-space between said member and said casing constructed to permit a regurgitation of a part of the flow delivered by said member, and an injector in said suction-passage actuated by said regurgitating flow.
3. In combination with a centrifugal pump having a runner, a casing therefor and a clearance-space between said runner and casing constructed to permit the regurgitation of a part of the delivered flow, an injector constructed to deliver fluid-supply to said

pump and actuated by said regurgitating flow.

4. In a centrifugal pump, a runner, a casing therefor, and an injector within said runner, delivering fluid-supply thereto.

5. In a centrifugal pump, a runner, a casing therefor, an injector within said runner for delivering fluid-supply thereto and a passage within said casing constructed to convey a part of the fluid-delivery of said pump to said injector to actuate the same.

6. In a pump, a moving liquid-impelling member and an injector delivering liquid to said member: the said injector having one of its concentric walls stationary and the other movable with said member.

7. In a pump, a moving liquid-impelling member and an injector delivering liquid to said member: the said injector having its inner nozzle stationary and its outer wall surrounding said nozzle, movable with said member.

8. In a pump, a rotary liquid-impelling member and an injector delivering liquid to said member: the said injector having one of its concentric walls stationary and the other rotary with said member.

9. In a pump, a rotary liquid-impelling member, a supply-duct therefor, and an injector delivering liquid to said member: the said injector having its inner nozzle on said supply-pipe and its outer surrounding wall on said rotary member.

10. In a pump, a rotary liquid-impelling member, an injector supplying liquid to said member and having one of its concentric walls stationary and the other rotary with said member, and means for conveying liquid from the delivery side of said impelling member to the space between said injector-walls.

In testimony whereof I have signed my name to this specification in the presence of two subscribing witnesses.

ALBERT E. GUY.
